UNITED STATES PATENT OFFICE.

OSCAR V. PAYNE, OF CLEVELAND, OHIO, ASSIGNOR TO AUTO ORDNANCE CORPORATION, OF NEW YORK, N. Y., A CORPORATION OF NEW YORK.

GUN ELEMENT.

1,358,104.

Specification of Letters Patent. Patented Nov. 9, 1920.

Application filed April 30, 1920. Serial No. 377,759.

To all whom it may concern:

Be it known that I, OSCAR V. PAYNE, a citizen of the United States of America, and resident of Cleveland, in the county of Cuyahoga, and State of Ohio, have invented new and useful Improvements in Gun Elements, of which the following is a specification.

My invention relates to an improved collar for gun elements adapted for use with guns of any size, but more particularly adapted for use with small arms. More specifically my invention consists in an improved separable means for providing a thrust collar adapted to be placed upon a firing pin to transmit to the pin the thrust of the firing spring.

In a large number of rifles and machine guns now in use, a bolt assembly is provided in which the firing pin is housed in the bolt, the rear portion of the pin being surrounded by a sleeve which is threaded into the rear of the bolt. In such devices the firing spring surrounds the pin and has its rear end bearing against the sleeve. It is necessary that the forward end of the spring be operatively connected to the firing pin and the connection should not be a permanent enlargement of the pin. This latter requirement is necessary in order to permit assembly and dismantling of the bolt mechanism, since it would otherwise be impossible to withdraw the firing pin through the sleeve and would be impractical to remove the spring over such a permanent enlargement.

It is an object of my invention to provide a new and improved separable thrust collar adapted for use with firing pins. It is also an object to provide a collar of the type described which is rigid and positive in its connection when assembled and yet which permits of ready and easy dismantling. It is a further object to provide such a collar which is simple in construction and relatively inexpensive to manufacture. Other and further objects will appear as the description proceeds.

I have shown a preferred embodiment of my invention in the accompanying drawings, in which—

Figure 1 is a section partly broken away of the breech mechanism of a gun illustrating the use of my device,

Fig. 2 is a view showing a firing pin with my thrust sleeve fitted thereon, the sleeve being shown in section,

Fig. 3 is a fragmentary view of a firing pin with the sleeve partly removed therefrom,

Fig. 4 is an end view of the sleeve,

Fig. 5 is a vertical section of the sleeve, 60 and

Fig. 6 is a section taken on line 6—6 of Fig. 2.

In order to clearly bring out the relation of my improved device, I have shown the 65 device in Fig. 1, in connection with a firearm, the latter forming no part of the present invention. The firearm shown comprises the barrel 7, receiver 8, magazine 9, fore piece 10, bolt 11, lock 12, sleeve 13, sear 14 70 and firing spring 15.

The firing pin 16 has the striker point 17, rear nose 18, thrust shoulder or enlargement 19, and reduced portion 24. My improved thrust sleeve has the reduced portion 20 substantially equal in diameter to the main portion of the firing pin 16, and the enlarged forward thrust bearing 21, the face of which is recessed at 22 to fit over the thrust shoulder 19 of the firing pin. The interior of the 80 sleeve is centrally bored at 23 to fit the reduced portion 24 of the firing pin, and the bore is carried out through the side of the sleeve at 25 so as to permit the sleeve to be moved laterally on to the firing pin. 85

When used in connection with the form of bolt mechanism shown, my device is assembled by first inserting the firing pin through the sleeve 13 from the rear. The spring 15 is next passed over the forward 90 end of the firing pin and placed with its rear end against the forward face of the sleeve 13. The spring is now pressed rearwardly until it clears the reduced portion 24 of the pin and the thrust sleeve is slipped laterally onto the pin as shown in Fig. 3. When the portion 24 of the pin is fully seated against the bore 23 the thrust sleeve is moved forward into the position shown in Figs. 1 and 2, the shoulder 19 resting in the 100 recess 22. The spring is now released and its forward end passes onto the sleeve and against the thrust bearing 21.

In this position the sleeve is restrained from movement both forwardly and laterally by the engagement with the thrust shoulder 19 of the overhanging shoulder, which surrounds the recess 22, and is further restrained from rearward movement by the force of the spring 15. It may, however, 110

be readily and quickly dismantled by a reversal of the assembly just described.

While I have shown and described my invention as a thrust sleeve for a firing pin, my particular form of connection is obviously of broader application and may be applied to other gun elements. I am aware that sleeves have heretofore been slipped laterally upon firing pins but such structures 10 having necessitated the use of a second circumferentially unbroken sleeve to be slipped on to the first sleeve to prevent lateral play or movement. In my structure no such second sleeve is necessary as the recess 22 in the sleeve by means of its engagement with the shoulder 19 effectively prevents play and eliminates any danger of the collar working loose from the pin.

I claim:

- 20 1. A firing pin having a circumferential thrust shoulder thereon, a thrust collar adapted to be laterally fitted to the pin, and having a recess in one end adapted to engage the thrust shoulder of the pin, and a spring 25 surrounding the pin and thrust collar and bearing against the latter to maintain the recess interfitted with the thrust shoulder.

2. A firing pin having a circumferential thrust shoulder thereon, a collar having a thrust enlargement thereon of greater diameter than the thrust shoulder on the pin, the collar being adapted to be laterally fitted to the pin, and having a recess adapted to engage the thrust shoulder on the pin, and a spring surrounding the pin and collar and bearing against the thrust enlargement of the latter to maintain the collar recess engaged with the thrust shoulder on the pin.

3. A firing pin having a circumferential thrust shoulder thereon, a collar having a thrust enlargement thereon of greater diameter than the thrust shoulder on the pin and having a reduced portion in rear of said enlargement, the collar being adapted to be laterally fitted to the pin and having a recess 45 adapted to receive the thrust shoulder on the pin, and a spring surrounding the pin and reduced portion of the collar and bearing against the thrust enlargement of the latter to maintain the collar recess engaged with the thrust shoulder on the pin.

Signed by me at Cleveland, Ohio, this 26th day of April, 1920.

OSCAR V. PAYNE.
